MERCURY SWITCH

Carl H. Larson, Elkhart, Ind., assignor to The
Adlake Company, a corporation of Illinois

Application July 21, 1933, Serial No. 681,408

16 Claims. (Cl. 200—112)

The principal object of this invention is to provide a heavy duty mercury switch capable of withstanding the destructive effects of high amperage loads.

5 Further and other objects and advantages will become apparent as the disclosure proceeds and the description is read in conjunction with the accompanying drawing, in which

Fig. 1 illustrates a front contact switch embodying the features of this invention, the switch being shown in de-energized position;

Fig. 2 is a view showing the same switch in energized position;

Fig. 3 is a plan view of the switch;

15 Fig. 4 is a perspective view of the displacer with the springs removed;

Fig. 5 illustrates a modified construction of the plunger;

Fig. 6 is a sectional view showing a time delay 20 front contact switch embodying the principles of this invention;

Fig. 7 shows the switch of Fig. 6 in energized position; and

Fig. 8 illustrates a circuit in which the switch 25 of this invention may be advantageously employed.

The sparking which occurs in a circuit breaker of any kind depends to a large extent upon the load which the circuit breaker carries. If the 30 load consists of a battery of lamps, there is likely to be considerable sparking when the circuit is being closed due to the initial surge in the circuit. If the circuit breaker carries an inductance load such as a motor or transformer, there will 35 be a tendency for an arc to form across the contacts when the circuit is being broken because of the inductance in the circuit. Other kinds of loads will produce other characteristic effects.

The present invention takes into account the 40 effect which various kinds of load have upon the arcing tendencies of a circuit breaker and provides a switch construction that can stand up over a long period of time under these severe and destructive conditions.

45 Tests have shown that a switch constructed in accordance with this invention will last ten times as long as a similar switch not embodying the improvements of this invention under an inductive load at 110 volts A. C. and 2 amperes.

50 It will be understood that the illustration and description of preferred forms of the invention are for the purpose of disclosure only and are not to be interpreted as imposing limitations upon the appended claims except as required by the 55 prior art.

Referring now to the drawing, and particularly to Figs. 1 and 2, the reference character 10 designates a coil which consists of a spool 11 over which a suitable number of turns of copper wire 12 are wound. The spool has a square central opening 13 that is adapted to receive an iron yoke 14 which passes through the coil and has radially extending arms 15 and 16 positioned one above the other. The ends of the arms are rounded as shown at 17 in Fig. 3 to conform to the 60 peripheries of the iron pole sleeves 18 and 19 which are held against the yoke by clips 20 secured to the arms 15 and 16 by nuts and bolts 21 or equivalent means. The pole sleeves are preferably made of Swedish iron and are adjustable 65 within the clips 20 so that the air gap 22 between their inner ends may be suitably located. Preferably the pole sleeves are provided with a slit 23 in order to prevent eddy currents from traveling around the sleeve when the relay is operating 70 on alternating current.

The yoke and pole sleeves for convenience may be called the iron or magnetic circuit of the relay, and it will be noticed that this circuit is closed except for the single air gap 22. 80

The iron circuit supports a mercury switch 24 which comprises a glass envelope 25 through the base of which electrodes 26 and 27 are pinch-sealed. The central electrode 26 is substantially on the axis of the envelope and is surrounded by 85 a glass insulating sleeve 28 which extends from the pinch seal 29 to a point 30 slightly below the top of the electrode. The bared portion 31 of the electrode 26 is bent over to one side as shown in the drawing, with the portion 32 extending below the top 30 of the insulating sleeve 28.

The switch envelope is preferably made of glass having a high melting point and a low coefficient of thermal expansion, such for example as the glass specified in Weintraub Patent No. 1,154,081. It is also preferred that the glass should be substantially free from compounds of lead, tin, antimony, and other substances which are decomposed by the action of an electric arc. 95

The electrodes 26 and 27 may be made of tungsten, molybdenum, tantalum, or any other electrode material having suitable properties of expansion and fusibility with the particular glass used in the envelope. 100

A quantity of purified mercury 33 is placed in the envelope during the process of manufacture and the amount is such that when the displacer or plunger, generally designated 34, is in the position shown in Fig. 1, the mercury level will be 110

below the depending portion 32 of the electrode 26.

Prior to sealing off the top of the switch, as shown at 35, the envelope is thoroughly evacuated, and a suitable gas fill is introduced. The gas fill may be helium, hydrogen, a physical mixture of helium and hydrogen, helium hydride, or any other suitable gas fill known to the art.

The switch envelope is held in proper position within the pole sleeves 18 and 19 by a resilient split sleeve 36 which engages the outer wall of the switch and frictionally holds it in place. The sleeve is of non-magnetic material and preferably is of brass.

15 The plunger or displacer 34 comprises an outer sleeve 37 of magnetic material, such as Swedish iron, and an inner sleeve 38 of refractory material such as high melting point glass, quartz, or ceramic material. The inner sleeve 38 fits 20 loosely within the outer sleeve and projects at both ends beyond the latter sleeve. The two sleeves are held in fixed relation by helical springs 39 and 40 which fit tightly over the projecting ends of the sleeve 38 and abut the ends 25 of the sleeve 37. Portions of the springs 39 and 40 extend beyond the ends of the sleeve 38 so that they not only serve to hold the sleeves in fixed relation, but also act as cushions for the plunger in its vertical movement within the 30 switch envelope.

35 The plunger 34 is guided in its movement within the envelope by lugs 41 which are formed on the outer sleeve 37. The sleeve is also preferably provided with a longitudinal slit 42 for the same reason that the pole sleeves are similarly slotted.

40 It will be understood that the plunger being partly composed of magnetic material responds to the energization of the coil 10 by moving downwardly to the position shown in Fig. 2 to close the air gap 22. This downward movement causes a displacement of mercury which brings the mercury level above the depending portion 32 of the central electrode and establishes an electrical connection between the central electrode 45 and the electrode 27, the latter being constantly in contact with the mercury. When the coil is de-energized, the plunger rises to the position shown in Fig. 1 and the electrical circuit through the electrodes 26 and 27 is again broken.

50 It has been found by experiment that when the bared portion 31 of the electrode is not bent over in the manner which has been described, but is vertical, there is a tendency for the top portion of the glass insulating sleeve 28 to disintegrate when the arcing between the electrode 26 and the mercury becomes severe under high amperage loads. This is particularly true when the switch is used in a circuit such as shown in Fig. 8 in which the switch carries a high inductive load.

55 The circuit shown in Fig. 8 is one which illustrates a thermostatic control for a motor, the control circuit being shown at 43 and the motor circuit at 44. Both circuits are energized from a power line 45 which may be 110 volts alternating current. The control circuit 43 operates on reduced voltage and includes a thermostatic switch 46, relay coil 47, and the secondary coil 70 48 of a step-down transformer 49. The motor circuit 44 includes the switch 24 and motor 50.

75 When the bared portion 31 of the electrode 26 is bent to one side so that a portion extends below the top of the insulating sleeve 28, the insulating sleeve 28 is protected from disintegrating

as the arc occurs directly between the mercury and the depending portion 32 of the electrode.

The plunger construction also assists in enabling the switch to withstand high amperage loads. The refractory material of which the inner sleeve 38 is made protects the magnetic sleeve 37 from the ravages of the electric arc and prevents the release of occluded gases from the magnetic sleeve. Since the refractory sleeve 38 fits loosely within the magnetic sleeve, there is poor heat conduction between the two, and this arrangement serves further to prevent the release of gases from the sleeve 37.

80 There are other advantages inherent in the plunger construction which has been described. The inner sleeve 38 being made of glass or other refractory material gives additional buoyancy to the plunger, and this is particularly desirable in a front contact switch.

85 The means for holding the inner and outer sleeves in fixed relation to one another produces no strain in the parts, and the difference in coefficients of expansion is unimportant. Heretofore, when glass sleeves have been cemented to magnetic sleeves, the heating effect of the arc necessarily produces a strain due to the difference in coefficients of expansion and oftentimes, the union of the two materials is disturbed. This cannot happen when the plunger is constructed in the manner taught by this invention.

90 Since the cement which is commonly used for uniting ceramic material to iron contains certain substances which are deleterious in a switch, there is a decided advantage in employing a construction which obviates the necessity of its use.

95 A further advantage is found in the fact that the springs 39 and 40 are not allowed to come in contact with the side walls of the envelope and gas pockets between the springs and the envelope are eliminated, as well as friction.

100 Obviously, the plunger may be modified and changed in detail in many ways without sacrificing the full advantages of the preferred form. For example, the top of the glass tube 38 may be provided with a flange 51, as shown in Fig. 5 so that the lower spring 40 alone secures the two sleeves together. The upper spring, then, would merely ride upon the top of the plunger.

105 Also it is possible for some of the advantages of this invention to be retained by making the outer sleeve of glass or similar material and the inner sleeve of magnetic material. In such an arrangement, the magnetic material would be subjected to the action of an electric arc, assuming that the electrode is on the inside of the plunger, and for this reason would be less desirable.

110 The invention is also applicable to time delay switches of the type shown in Figs. 6 and 7. The structure of the switch shown in these two figures is identical in all respects to the switch shown in Figs. 1 and 2 with the exception that a porous ceramic thimble 52 is substituted for the glass sleeve 38. In this type of switch, as soon as the relay coil is energized, the plunger, here designated 53, is drawn downwardly to the position shown in Fig. 7 but due to the entrapment of gas within the thimble 52 and its slow escape through the pores of the ceramic material, the mercury within the thimble is first forced downwardly away from the bared portion 31 of the electrode while at the same time the mercury on the outside of the plunger rises to a level substantially above the top of 150

the electrode. As the gas pressures on the inside and outside of the thimble are equalized, the mercury levels also equalize so that after a given period of time, depending upon the density of the 5 ceramic material, the mercury will take the position shown in Fig. 7 and the circuit will be established between the two electrodes.

In a similar manner, when the relay coil is de-energized, the plunger will rise to a point slightly 10 below the position of the plunger shown in Fig. 6 carrying with it a column of mercury on the inside and as gas enters the interior of the thimble, due to unequal gas pressure, the mercury level recedes below the bared portion of the central 15 electrode, while at the same time the plunger rises to the position shown in Fig. 6. When the plunger is in this position, the mercury levels on the inside and outside of the plunger have been equalized.

20 The invention is susceptible of many modifications within the scope of the appended claims.

What I claim, therefore, is:

1. In a mercury switch, a vertical switch envelope, spaced electrodes sealed through the envelope, a quantity of mercury in the envelope adapted to make or break an electrical circuit through the electrodes according to its level, and a displacer for changing the mercury level comprising telescoping magnetic and refractory members, one of which projects beyond the other, and means for holding the members in fixed relation, said means including a helical spring fitted over the end of the projecting member.

2. In a mercury switch, a vertical switch envelope, spaced electrodes sealed through the envelope, a quantity of mercury in the envelope adapted to make or break an electrical circuit through the electrodes according to its level, and a displacer for changing the mercury level comprising telescoping magnetic and refractory members, one of which projects at both ends beyond the other, and means for holding the members in fixed relation, said means including helical springs fitted over opposite ends of the projecting member.

3. In a mercury switch, a vertical switch envelope, spaced electrodes sealed through the envelope, a quantity of mercury in the envelope adapted to make or break an electrical circuit through the electrodes according to its level, and a displacer for changing the mercury level comprising loosely telescoping magnetic and refractory members one of which projects beyond the other, and means for holding the members in fixed relation, said means including a helical spring fitted over the end of the projecting member and abutting the end of the other member.

4. In a mercury switch, a vertical switch envelope, spaced electrodes sealed through the envelope, a quantity of mercury in the envelope adapted to make or break an electrical circuit through the electrodes according to its level, and a displacer for changing the mercury level, said displacer having an outside diameter slightly less than the inside diameter of the envelope and comprising telescoping sleeves of magnetic and refractory material, the inner one of which projects beyond the outer one, and means for holding the sleeves in fixed relation, said means including a helical spring fitted over the projecting end of the inner sleeve.

5. In a mercury switch, a vertical switch envelope, spaced electrodes in the envelope, one of which is substantially axially located, a quantity of mercury in the envelope adapted to make or

break an electrical circuit through the electrodes according to its level, a displacer telescoped over the axial electrode for changing the mercury level, said displacer comprising an exterior sleeve of magnetic material, an interior loosely fitting sleeve of refractory material, and friction means for holding the sleeves in fixed relation to each other.

6. A displacer for use in mercury switches comprising telescoping magnetic and refractory members, one of which projects beyond the other, and means for holding the members in fixed relation, said means including a helical spring fitted over the end of the projecting member.

7. A displacer for use in mercury switches comprising loosely telescoping magnetic and refractory members one of which projects beyond the other, and means for holding the members in fixed relation, said means including a helical spring fitted over the end of the projecting member and abutting the end of the other member.

8. In a mercury switch, a vertical switch envelope, a pair of upstanding spaced electrodes in the envelope, one of which is substantially axially located and is surrounded by an insulating sleeve to a point adjacent the top of the electrode, a quantity of mercury in the envelope adapted to make or break an electrical circuit through the electrodes according to its level, a displacer telescoped over the axial electrode for changing the mercury level, said displacer comprising an outer sleeve of magnetic material, and an inner sleeve of refractory material, the bared end of said axial electrode being bent over to one side with a portion extending below the top of the insulating sleeve whereby the insulating sleeve is protected from the ravages of the electric arc which tends to form when the electrical circuit is being opened and closed.

9. In a mercury switch, a vertical switch envelope, a pair of upstanding spaced electrodes in the envelope, one of which is substantially axially located and is surrounded by an insulating sleeve to a point adjacent the top of the electrode, a quantity of mercury in the envelope adapted to make or break an electrical circuit through the electrodes according to its level, a displacer telescoped over the axial electrode for changing the mercury level, the bared end of said axial electrode being bent over to one side with a portion extending below the top of the insulating sleeve whereby the insulating sleeve is protected from the ravages of the electric arc which tends to form when the electrical circuit is being opened and closed.

10. In a mercury switch, a vertical switch envelope, spaced electrodes in the envelope, a mercury fill, a displacer for changing the mercury level, one of said electrodes being insulated to a point adjacent the top of the electrode and having its bared end bent over to one side with a portion extending below the top of the insulation.

11. In a mercury switch, a vertical switch envelope, spaced electrodes in the envelope, a mercury fill, and a displacer for changing the mercury level, said displacer including telescoping sleeves of magnetic and refractory material, and a helical spring for holding the sleeves in fixed relation.

12. In a mercury switch, a vertical switch envelope, spaced electrodes in the envelope, a mercury fill, and a displacer for changing the mercury level, said displacer including telescoping

sleeves of magnetic and refractory material, and a helical spring for holding the sleeves in fixed relation, said spring projecting beyond the end of the displacer to cushion the displacer when moved to impact with the end of the envelope.

13. In a mercury switch, a vertical switch envelope, spaced electrodes in the envelope, a mercury fill, a displacer for changing the mercury level, one of said electrodes being insulated to a point adjacent the top of the electrode and having a portion of its bared end extending below the top of the insulation.

14. In a mercury switch, a vertical switch envelope, spaced electrodes in the envelope, a mercury fill, and a displacer for changing the mercury level, said displacer including telescoping sleeves of magnetic and refractory material, the inner sleeve projecting beyond the other, and a

helical spring fitted over the projecting end of the inner sleeve.

15. In a mercury switch, a vertical switch envelope, spaced electrodes in the envelope, a mercury fill, and a displacer for changing the mercury level, said displacer including telescoping members of magnetic and refractory material, the inner member projecting beyond the other, and a helical spring fitted over the projecting end of the inner member.

16. In a mercury switch, a vertical switch envelope, spaced electrodes in the envelope, a mercury fill, a displacer for changing the mercury level, one of said electrodes being insulated to a point above the low level of the mercury and having its bared end extended below the top of the insulation.
